(57) **CLAIM**

The ornamental design for a button configuration, as shown and described.

DESCRIPTION

FIG. 1 is a perspective view of a button configuration showing my new design;

FIG. 2 is a front view of the design;

FIG. 3 is a bottom plan view of the design;

FIG. 4 is a right side view of the design;

FIG. 5 is a left side view of the design;

FIG. 6 is a top plan view of the design;

FIG. 7 is a perspective view of another embodiment of the design;

FIG. 8 is a front view of another embodiment of the design;

FIG. 9 is a bottom plan view of another embodiment of the design;

FIG. 10 is a right side view of another embodiment of the design;

FIG. 11 is a left side view of another embodiment of the design; and,

FIG. 12 is a top plan view of another embodiment of the design.

Broken lines are for illustrative purposes only and form no part of the claimed design.
